UNITED STATES PATENT OFFICE.

WERNER F. ROTHERMUND, OF NEW YORK, N. Y.

DESIGN FOR A CUP.

No. 39,556.

Specification for Design.

Patented Sept. 22, 1908.

Application filed May 20, 1908. Serial No. 433,957. Term of patent 7 years.

To all whom it may concern:

Be it known that I, WERNER F. ROTHERMUND, a citizen of the United States, residing at No. 1228 Sterling Place, in the borough of Brooklyn, city of New York, county of Kings, and State of New York, have invented a new, original, and ornamental Design for a Cup, of which the following is a specification, reference being had to accompanying drawing, forming part thereof.

The figure is a perspective view showing the design of the cup.

As shown in the drawing the leading or material feature of my design, consists of a cup, having for a base support, a representation of a stump or lower part of a tree, with roots, knots and bark; said cup also having handles representing a branch or limb of a tree with knots and bark.

I claim—

The ornamental design for a cup as shown and described.

WERNER F. ROTHERMUND.
